UNITED STATES PATENT OFFICE.

JOHN H. BURNS, OF YELM, WASHINGTON, ASSIGNOR OF ONE-THIRD TO ALFRED MORRIS
AND ONE-THIRD TO ALFRED LEE MORRIS, BOTH OF YELM, WASHINGTON.

WORK-HOLDER.

1,244,419.

Specification of Letters Patent. Patented Oct. 23, 1917.

Application filed November 29, 1915, Serial No. 64,145. Renewed September 4, 1917. Serial No. 189,681.

To all whom it may concern:

Be it known that I, JOHN H. BURNS, a citizen of the United States, residing at Yelm, in the county of Thurston and State of Washington, have invented certain new and useful Improvements in Work-Holders, of which the following is a specification, reference being had to the accompanying drawings.

10 This invention relates to certain improvements in work holders, and it is an object of the invention to provide a novel and improved device of this general character especially designed and adapted for use in connection with doors, windows or the like when it is desired to brace the same.

Furthermore, it is an object of the invention to provide a work holder of this general character having novel and improved means whereby the same may be compacted within a minimum of space when not in use and whereby the same may be applied in operative position with convenience and facility.

The invention consists in the details of 25 construction and in the combination and arrangement of the several parts of my improved work holder whereby certain important advantages are attained and the device is rendered simpler, less expensive and otherwise 30 more convenient and advantageous for use, all as will be hereinafter more fully set forth.

The novel features of the invention will be carefully defined in the appended claims.

35 In order that my invention may be the better understood, I will now proceed to describe the same with reference to the accompanying drawings, wherein—

Figure 1 is a view in perspective illustrating 40 a work holder constructed in accordance with an embodiment of my invention, a second position of certain of the parts of the device being indicated by dotted lines;

Fig. 2 is a view in bottom plan of my improved work holder in a folded or compacted adjustment; and

Fig. 3 is an enlarged detail view illustrating certain features of the invention as herein embodied.

50 As disclosed in the accompanying drawings, 1 denotes an elongated strip of material having its forward end upturned, as at 2, to afford a stop against which the work is adapted to abut and said strip 1 adjacent 55 the upturned portion 2 is provided with the

depending penetrating member 3 which is adapted to impinge a supporting surface so as to prevent movement of the strip 1 when the work is being operated upon and especially during a planing operation. 60

Arranged transversely of the strip 1 at a point rearwardly of the upturned portion 2 is the plate 4 which extends beyond the opposite faces of the strip 1 and has one of its end portions upturned, as at 5, and pivotally 65 secured to the extended portions of the plate 4 are the elongated strips 6 and 7. The strip 6 has disposed therethrough adjacent its opposite ends the upstanding threaded members 8 with which coat the winged clamping nuts 9 adapted to engage the extremities of the holding member H. As herein embodied, the holding member H comprises a vertical strip 10 having its lower extremities terminating in an outwardly disposed and 70 perpendicularly related extension or extremity 11 adapted to rest upon the upper surface of the strip 6 and provided with a longitudinally disposed slot 12 through which one of the threaded members 8 extends. The upper end portion of the strip 10 is returned, as at 14, and is then extended outwardly and downwardly on an incline, as at 15, and terminates in the extension or extremity 16 perpendicularly related to the 75 strip 10 and provided with a longitudinally disposed slot 17 through which the second threaded member 8 is directed. By this arrangement, it will be perceived that the holding member H may be readily and 80 conveniently adjusted relative to the strip 1 or more particularly the work adapted to be engaged by my device. It is also to be observed that the strip 6 has its pivoted extremity resting upon the upper surface 85 of the plate 4 and has its outer or free end provided with the depending lip or flange 18 whereby the device may be properly set upon a supporting surface without interference being offered by the heads 19 of the 90 threaded members 8.

The strip 7 underlies the plate 4 and has its outer end returned, as at 20, to afford a spring action and is then extended upwardly and inwardly, as at 21, on a predetermined 105 incline and terminates in the downwardly disposed strip 22, the lower extremity of said strip 22 being provided with the in-turned flange or lip 23 with which the work is adapted to engage and whereby said 110

work will be effectively held between the holder H and the holder H' as it will be perceived that the work when inserted between the holders H and H' will contact 5 with the flange or lip 23 and cause the holder H' to move toward the holder H. It will also be readily appreciated that the normal position of the holder H' under the influence of the spring 20 affords a separation 10 between the upper extremities of the holders H and H', or more particularly the strips 10 and 22, which facilitates the insertion of the work between the strips 10 and 22. It will be understood that the 15 holder H' comprises the strip 22 and its concomitant parts. It is also to be observed that the lip or flange 23 is adapted to engage the upper face of the plate 4 inwardly of the flange or lip 5 and said flange 20 or lip 5 serves to limit the outward spring movement of the strip 22.

From the foregoing description, it is thought to be obvious that a work holder constructed in accordance with my invention 25 is of an extremely simple and comparatively inexpensive nature and is particularly well adapted for use by reason of the convenience and facility with which it may be assembled, and it will also be obvious that 30 my invention is susceptible of some change and modification without material departure from the principles and spirit thereof and for this reason I do not wish to be understood as limiting myself to the precise arrangement and formation of the several 35 parts herein shown in carrying out my invention in practice.

I claim:

1. A work holder comprising an elongated strip provided with a stop, and work engaging members pivotally engaged with said strip at a point inwardly of the stop, one of said work engaging members comprising a strip resiliently supported by the 45 engaging member normally maintained elevated and on an upward and outward incline relative to the coacting work engaging member, the lower extremity of said vertical strip terminating in an inturned lip adapt-

ed to be engaged by the work when inserted 50 between the engaging members, whereby the strip is moved downwardly and toward the coacting engaging member.

2. A work holder of the character described comprising an elongated strip provided with a stop, a plate disposed transversely of the strip and extending beyond opposite sides thereof, one end portion of the plate being provided with an upturned lip, work engaging members pivotally engaged with the plate at opposite sides of the strip, one of said work engaging members including a resiliently supported vertical strip normally maintained elevated and on an upward and outward incline, the lower extremity of which being provided with an inturned lip adapted to rest upon the plate inwardly of the lip of the plate, said last named lip being engageable with the work when inserted between the engaging members, whereby the strip is moved downwardly and toward the coacting engaging member, the first named lip preventing outward movement of the lower end of the resiliently supported strip when in 70 its lowered position.

3. A work holder comprising two relatively spaced work engaging members, one of said work engaging members including an elongated strip of material having its 80 outer end returned and continued upwardly on a predetermined incline and terminating in a downwardly disposed strip adapted to contact with the work inserted between the work engaging members, the lower end of the downwardly disposed strip being free and terminating in an inwardly disposed lip adapted to be engaged by the work for forcing the strip downwardly and in a direction toward the coacting work engaging 85 members.

In testimony whereof I hereunto affix my signature in the presence of two witnesses.

JOHN H. BURNS.
